UNITED STATES PATENT OFFICE.

JAMES M. COCHRAN, OF JACKSON, TENNESSEE.

WRENCH.

SPECIFICATION forming part of Letters Patent No. 527,592, dated October 16, 1894.

Application filed June 11, 1894. Serial No. 514,201. (No model.)

To all whom it may concern:

Be it known that I, JAMES M. COCHRAN, a citizen of the United States, residing at Jackson, in the county of Madison and State of Tennessee, have invented certain new and useful Improvements in Wrenches; and I do hereby declare the following to be a full, clear, and exact description of the invention, such as will enable others skilled in the art to which it appertains to make and use the same.

My invention has relation to wrenches adapted especially to be used for turning pipes, but it can be used for turning nuts, bolts, &c., and it consists in the novel construction and arrangement of its parts as hereinafter described.

In the accompanying drawings: Figure 1, is a side view of the wrench. Fig. 2, is a cross sectional view of the wrench at the pivot point of the two jaws. Fig. 3, is a perspective view of the link used to hold the jaws together. Fig. 4, is a detail view of the spring adapted to press the jaws apart.

The wrench consists of the lower jaw 1, the rear end of which forms the handle of the wrench. The said jaw is provided with the integral protrusion 2, provided with the notches 3, and the integral perforated lug 4.

The upper jaw 5, is pivoted to the lug 4, by means of a bifurcated end in which the lug rests, and the bolt 6, which passes through the bifurcated end and lug 4. The spring 7 is also provided with a bifurcated end having the curved points, 8, 8, by means of which said spring is secured at the pivot point between the two jaws. The other end of the spring is arched as shown and is adapted to keep the free ends of the jaws apart. The jaw 5, is also provided with the integral protrusion 9, similar to the protrusion 2. The protrusion 9, is also provided with the notches 10. The free ends of the jaws 1, and 5, are enlarged by making them thicker transversely from the line 11, 11, to the ends. Said en-

largements keep the link 12, from slipping off the jaws and also strengthen the ends of the jaws. The protrusions 2, and 9, also strengthen the jaws. The link 12, consists of the perpendicular sides formed with integral end portions 13, 13. The inner longitudinal sides of the end portions converge to an edge. (See Fig. 1.) Said end portions 13, are adapted to rest in the notches 10, and 3, of the protrusions of the jaws.

The gripping portion of the jaw 5, is provided with the teeth 14, and the gripping portion of the jaw 1, may also be provided with similar teeth if desired.

The wrench is operated as follows: To close the jaws 1, and 5, about a pipe, nut or bolt; the said jaws are pressed together about the object to be turned and the link moved up in the notches. Thus the wrench is made to fit and grasp the object.

Having described my invention, what I claim as new, and desire to secure by Letters Patent, is—

A wrench having its jaws pivoted together a perpendicular protrusion on each jaw having notches, and a transverse enlargement on each jaw extending from the end of the jaw to about the beginning of the perpendicular protrusion; a link adapted to surround the jaws and work in the notches of the protrusions; said transverse enlargements adapted to prevent the link from slipping from the jaw; an arch spring located between the jaws, said spring having a bifurcated end with curved points, said bifurcation adapted to fit around the pivot lug on one jaw and the end of the other jaw adapted to bear against said curved points, as set forth.

In testimony whereof I affix my signature in presence of two witnesses.

JAMES M. COCHRAN.
